UNITED STATES PATENT OFFICE.

ARTHUR L. HALLIDAY, OF YONKERS, NEW YORK, ASSIGNOR TO THE
BIGELOW CARPET COMPANY, OF CLINTON, MASSACHUSETTS.

DESIGN FOR A CARPET.

SPECIFICATION forming part of Design No. 13,251, dated August 22, 1882.

Application filed July 28, 1882. Term of patent 3½ years.

To all whom it may concern:

Be it known that I, ARTHUR L. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

H is a stripe containing an ornamentation composed of a series of figures, a, resembling rounded arches, within which are set different leaf-like or flower-like figures in succession, each of these figures being set on a stem springing from the figure b, which last consists of a pair of curling tendrils, one on each side of the stem. Below these series of figures b runs the band c, ornamented with an angular pattern.

The stripe D contains an ornamentation consisting of a band, e f, running alternately up and down at nearly right angles, and leaving spaces alternately above and below the band, in each of which is set a figure, d, resembling a butterfly. Below the band e f runs a chain or band, g, of daisy-like flowers, and below this flower chain g is the panel M, containing a branch, h, bearing a flower and surrounding leaves, and also a bunch of flowers, i. This

panel M is repeated, the successive panels M being separated from each other by the figure n, while along the bottoms of these panels runs the rectangular recessed border o, below which is the dotted band P.

I claim—

1. The design for carpets, consisting of the stripe H, containing figures a b c, substantially as shown. 40
